(57) **CLAIM**

The ornamental design for a decorative panel for building as shown and described.

DESCRIPTION

FIG. 1 is a front view of the decorative panel thereof shown in a condition of use, with the decorative panel being used in conjunction with a second broken line decorative panel; FIG. 2 is a front view of an embodiment of a decorative panel for building according to my new design; FIG. 3 is a left side view thereof; FIG. 4 is a bottom perspective view thereof; and, FIG. 5 is an enlarged, partial view of the building panel showing the portion within area 5 of FIG. 2.

The faded portion surrounded by broken lines in FIG. 1 illustrates an additional panel that forms no parts of the claimed design. The dot-dash lines of FIGS. 2 and 5 depict the boundaries of an enlargement and form no part of the claimed design.
